UNITED STATES PATENT OFFICE

VICTOR GEORGE WILLIAM GILBERT, OF LONDON, ENGLAND, ASSIGNOR TO AMERICAN-
LA FRANCE AND FOAMITE CORPORATION, OF NEW YORK, N. Y., A CORPORATION OF
NEW YORK

FIRE EXTINGUISHER

Application filed April 23, 1930, Serial No. 447,875, and in Great Britain April 30, 1929.

The object of the invention is an improved foam extinguisher of the invertible type, in which an externally operated stopple is adapted to close both the discharge outlet and the so-called inner container and having novel provision for mounting the inner container, more particularly in its relation to the discharge nozzle, for securing the inner container against displacement when the apparatus is inverted and for facilitating removal of the stopple or valve member which normally closes that container, all as illustrated in preferred form in the accompanying drawing.

Fig. 1 is a vertical section of an extinguisher having the invention applied and

Fig. 2 a horizontal section on the line II—II of Fig. 1.

The outer solution container 1 is provided with the usual closure cap 2 having threaded connection with the neck casting 3, which is preferably arranged to support the inner removable container 4. To that end a seat structure 5 in the form of a ring is located below the neck opening and spaced from it by depending cage bars 6 which, together with the structure 5, may be cast integrally with the neck. The bars are set approximately flush with the neck opening so as to leave it entirely unobstructed to receive a stopple or valve-member 6a of a diameter substantially equal to that of the neck. The stopple is manually operated by any appropriate means, being shown attached to a stem 7 which passes through a gland 8 in the cap 2 and terminates in a knob 9 having a bayonet slot 10 for engagement with pin 11 when the knob is depressed.

The ring structure 5 constitutes a combined support, for the inner container, and a discharge fitting and in its latter function embodies an enlargement 12 which projects inwardly, to bring its upper face within the projection of the neck opening and beneath the stopple, and which has a discharge outlet 13 in that face communicating with the nozzle 14. The nozzle is also a part of the neck-ring casting and projects outwardly to and through the dome of the outer container. By reason of the large diameter stopple

which the neck and the bars 6 accommodate, the top face of the enlargement 12 can accommodate an adequately sized foam outlet without encroaching unduly on the space within the ring which is occupied by the inner container 4 and the latter is formed with a groove or reentrant portion 15 extending its full length and dimensioned to embrace or accommodate enlargement 12, as indicated, so as to permit the container to be withdrawn through the neck opening.

The top face of the ring structure constitutes a part of the seat for the stopple, which jointly opens and closes both the foam discharge outlet and the inner container, for which purpose the latter is arranged to be supported with its upper end flush with the top of the ring thus to be engaged and closed by the flat face of the stopple. Preferably this is accomplished by means of a spacer ring 16 secured to the inner container and so dimensioned that when the top of the latter occupies the desired position with respect to the seat face of the ring structure the bottom of the spacer ring seats on a shelf or a number of lugs 17 which project inwardly from the lower end of ring 5. The depth of rings 5 and 16 is usually adequate to steady the container 4 against lateral movement but other provision for that purpose may be made if desired.

To hold the inner container against longitudinal movement when the extinguisher is inverted, I provide a compression spring 18, the lower end of which bears against a cross-bar 19 arranged just below the top of container 4 and by means of which bar the container can readily be withdrawn for cleaning. In the preferred form illustrated the upper end of spring 18 bears against and may be secured to the face of the stopple so as to lift the same and open the container and outlet as soon as stem 7 is released, while still holding the container against its seat in the ring structure. In this respect spring 18 serves to assist the usual valve spring 20.

Having now described my invention, I claim:

1. In a fire extinguisher the combination of an outer container, an inner container sup-

porting-member therein, a stopple adapted to seat on an upper face of said member, said face having an outlet for foam discharge, an inner container adapted for support on said member and having a seat arranged for engagement with said stopple when the same is in engagement with said surface.

2. In a fire extinguisher having inner and outer solution containers, the combination of 10 a neck casting for the latter having a depending ring structure adapted to support said inner container and a neck opening above said ring structure through which said inner container is removable, an externally operated stopple adapted to engage and close the inner container and also to seat on the upper surface of said structure and a discharge nozzle connected with an outlet in the seat face of said ring structure and also 20 closed by said stopple.

3. A fire extinguisher comprising an outer solution container, a neck casting therein having depending cage bars and a ring supported thereby, an inner container arranged to 25 seat on said ring with its upper end below the neck opening, a discharge outlet in the upper face of said ring, a stopple of substantially the full diameter of the neck adapted to overlie and close both the inner container and the discharge outlet and means for holding the inner container against its seat when the extinguisher is inverted.

4. The combination set forth in the preceding claim in which the inner container rests 35 with its upper end flush with the upper surface of said ring and is held against its seat by a spring.

5. In a fire extinguisher, the combination of inner and outer solution containers, said 40 outer container having a neck opening for the insertion of the inner container and also having a seat structure depending from the neck arranged to support said inner container, a stopple for the latter, a spring urging 45 the stopple toward its open position and also engaging the inner container to hold it on its seat, a closure cap for said neck opening and stopple operating means carried thereby.

6. In a fire extinguisher the combination 50 of an outer solution container having a neck opening and a closure cap therefor, an inner container insertable through said opening, a stopple and means normally holding the same in position to close the inner container and a spring bearing on the latter to hold the same against displacement when the extinguisher is inverted, said spring also arranged to open the stopple when said holding means is released.

60 7. In a fire extinguisher the combination of an outer container having a neck opening, an inner container insertable and removable through said opening, said inner container having a reentrant portion or groove extending 65 the length thereof, a foam outlet member

normally occupying said groove and a common stopple jointly seating on said inner container and on said outlet member.

In testimony whereof, I have signed this 70 specification.

VICTOR GEORGE WILLIAM GILBERT.
